UNITED STATES PATENT OFFICE

WILLIAM T. GUTH, OF BROOKLYN, NEW YORK

DESIGN FOR A COMBINED FENDER AND TIRE HOLDER

Application filed November 9, 1931. Serial No. 41,671. Term of patent 14 years.

To all whom it may concern:

Be it known that I, WILLIAM T. GUTH, a citizen of the United States, residing in Brooklyn, county of Kings, and State of New York, have invented a new, original, and ornamental Design for a Combined Fender and Tire Holder, of which the following is a specification, reference being had to the accompanying drawings, forming a part thereof.

In the drawings:

Figure 1 is a plan view of the combined fender and tireholder; and

Figure 2 is a side elevation of the same.

The salient feature of the invention lies in the construction of the fenders, the tire carrier and the running board upon lines to give the suggestion of speed. To this end

the front fender is relatively flat at the top. The rear fender is drawn out at the rear. The tire carrier is relatively flat at the top and bottom, and at the bottom is drawn out to the rear for a substantial distance. The running board has a series of elongated slots along the side thereof of progressively diminishing length from front to rear.

The present application is a continuation in part of my pending application Serial No. D.38,963, filed March 6, 1931, for combined fender and tire holder.

I claim:

The ornamental design for a combined fender and tire holder substantially as shown and described.

WILLIAM T. GUTH.
